UNITED STATES PATENT OFFICE

168,204

BLOUSSETTE OR SIMILAR ARTICLE

Milton R. Anthony and Dorothy Calvacca,
New York, N. Y.

Application May 22, 1952, Serial No. 19,837

Term of patent 7 years

(Cl. D3—25)

To all whom it may concern:

Be it known that we, Milton R. Anthony and Dorothy Calvacca, both citizens of the United States of America and residents of New York city, county of New York, and State of New York, have invented a new, original, and ornamental Design for a Blousette or Similar Article, of which the following is a specification, reference being had to the accompanying drawing, forming part thereof, wherein,

We claim:

The ornamental design for a blousette or similar article, substantially as shown.

MILTON R. ANTHONY.
DOROTHY CALVACCA.
